ATTORNEYS

UNITED STATES PATENT OFFICE.

HERMAN D. SEITZMAN, OF BROOKLYN, NEW YORK.

WRENCH.

1,325,380.

Specification of Letters Patent. Patented Dec. 16, 1919.

Application filed August 5, 1919. Serial No. 315,506.

To all whom it may concern:

Be it known that I, HERMAN D. SEITZMAN, a citizen of the United States, and a resident of the city of New York, borough 5 of Brooklyn, county of Kings, have invented a new and Improved Wrench, of which the following is a full, clear, and exact description.

This invention relates to improvements in 10 wrenches, an object of the invention being to provide a wrench having improved means for adjusting and holding the movable jaw so that when once adjusted the jaws will not slip but will securely hold the nut or pipe 15 with which they are in engagement.

A further object is to provide a wrench which may be used in connection with any 20 form or shape of nut, bolt head, or pipe, and which will efficiently perform its functions in all uses.

A further object is to provide a wrench which will be extremely simple in construction, which can be manufactured at a reasonably low price, which is not liable to get 25 out of order, and which will be extremely strong and durable in use.

With these and other objects in view, the invention consists in certain novel features of construction and combinations and arrangement of parts as will be more fully 30 hereinafter described and pointed out in the claims.

In the accompanying drawings, Figure 1 is a view in side elevation partly in section 35 illustrating one form of my invention.

Fig. 2 is an edge view at right angles to Fig. 1.

Fig. 3 is a fragmentary view of the opposite edge of the wrench shown in Fig. 1.

Fig. 4 is a fragmentary view showing the opposite side of the jaws shown in Fig. 1.

Fig. 5 is a view in transverse section on the line 5—5 of Fig. 1.

Fig. 6 is a perspective view of the split 45 collar 12.

Fig. 7 is a fragmentary view in side elevation illustrating a modification of my invention in which the jaws are to be used for engaging a pipe.

Fig. 8 is a fragmentary view in section on the line 8—8 of Fig. 7.

1 represents a handle rod having a fixed jaw 2 at one end and milled hand hold 3 at its other end. The hand hold end 3 is provided with a socket 4 adapted to receive the shank 5 of any approved tool, and may be

utilized with various tools as will be readily understood. The rod 1 has flat sides 6 and is screw threaded throughout a portion of its length as shown at 7. 8 represents a movable jaw which is made with an integral boss 9 movable on the rod 1 and having flat faces 10 located against the flat sides 6 of the rod, so that while the jaw is free to move longitudinally of the rod, it is held 65 against the possibility of turning movement thereon.

An adjusting sleeve 11 is positioned on the rod 1 and has internal screw threads 11' engaging the screw threads 7 so that the 70 turning movement of the sleeve causes the same to move longitudinal of the rod.

A split collar 12 is secured to the sleeve 11 by means of screws 13, and has an inwardly projecting annular flange 15 which 75 engages an annular flange 16 on the boss 9, the flange 15 coöperating with the end of sleeve 11 to compel the jaw 8 to move longitudinally when the sleeve 11 is turned.

The jaws 2 and 8 are located at right angles to the rod 1 and project beyond both sides thereof. These jaws are provided with a plurality of pairs of opposed angular recesses 16, 17, 18, and 19 in the sides and ends of the jaws 2 and 8 and these pairs of 85 recesses are of different angular formations to accommodate any ordinary angular nut or bolt head in common use.

In the modification illustrated in Figs. 7 and 8, the fixed jaw 20 and movable jaw 21 90 are made with toothed recesses 22 and 23 respectively to engage a pipe. Thus this form of my invention constitutes a pipe wrench. The toothed recess 23 of the movable jaw 21 is provided in a movable portion 21' of the jaw, this movable portion 21' having a perforated ear 24 located between a pair of perforated ears 25 on the boss 30 and pivotally connected by means of a pin 26. The ear 24 has a beveled shoulder 100 27 which limits its pivotal movement and a spring 28 is secured by a screw 29 to the boss 30, and holds the movable jaw 21' in normal position.

This pivotal movement of the portion 21' 105 of jaw 21 permits the wrench to be released from the pipe in its movement in one direction as is necessary with devices of this character.

The split collar 12 above referred to is 110 preferably split at an angle as shown clearly in Fig. 6, which gives to the device an added

strength over an ordinary straight split collar to sustain the strains and stresses of the movable jaw.

The two halves of the split collar can, of course, be inserted from opposite sides to permit a quick connection of the sleeve with the jaw, and the angularly disposed contacting surfaces sustain longitudinal strains when the sleeve is forced in one direction to 10 press the jaws into operative position. They also sustain the strain in the opposite direction during the manipulation of the jaws.

While I have illustrated what I believe to be preferred embodiments of my invention, I would have it understood that I do not limit myself to the precise detail set forth, but consider myself at liberty to make such changes and alterations as fairly fall within the spirit and scope of the appended 20 claims.

Having thus described my invention, what I claim as new and desire to secure by Letters Patent, is:

1. A wrench, comprising a handle rod 25 having a fixed jaw at one end, said rod having a screw threaded portion, a movable jaw mounted to move on the rod and held against rotary movement thereon, a boss on the movable jaw, an annular flange on the 30 boss, a screw threaded sleeve engaging the rod, a split collar having its members secured to the sleeve, and an internal annular flange on the split collar engaging over the flange of the movable jaw.

2. A wrench of the character described, comprising a handle rod, a fixed jaw on one end of the rod, said rod having a screw threaded portion and having flat sides, a movable jaw having a boss thereon, said boss 40 receiving the rod and having flat faces engaging the flat sides of the rod, an adjusting sleeve having internal screw threads engag-

ing the threads of the rod, a split collar secured to the sleeve and engaging the boss whereby the movable jaw is compelled to 45 move on the rod when the sleeve is turned.

3. A wrench, comprising a handle rod having flat sides, a fixed jaw on one end of the rod, a movable jaw, a boss on the movable jaw receiving the rod, said boss and rod 50 having flat faces whereby the jaw is held against rotary movement on the rod, an annular flange on the boss, a sleeve, said sleeve and rod having a screw threaded engagement, a split collar secured to the sleeve, and 55 an internal annular flange on the collar engaging over the flange of the jaw whereby the movable jaw is compelled to move longitudinally of the rod when the sleeve is turned.

4. A wrench, comprising a handle rod, a fixed jaw on one end of the rod, a movable jaw on the rod, means for preventing rotary movement of the movable jaw on the rod, an adjusting sleeve on the rod, said sleeve and 65 rod having a screw threaded engagement, a diagonally split collar connecting the sleeve and movable jaw, said jaws projecting on both sides of the rod and having in their ends and sides pairs of opposed angular 70 recesses.

5. A wrench, comprising a handle rod, fixed jaw on the rod, a movable jaw on the rod, an adjusting sleeve having screw threaded connection with the rod, a diagonally split collar connecting the sleeve and the movable jaw, a pivotally supported section on the movable jaw having a limited movement relative to the jaw, a spring holding said movable section in one position, and 80 said movable section and fixed jaw having opposed toothed pipe receiving recesses.

HERMAN D. SEITZMAN.
